[57] CLAIM

The ornamental design for a handle for a plumbing fitting, as shown and described.

DESCRIPTION

FIG. 1 is a right, top, front perspective view of embodying our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a left, top, front perspective view of a second embodiment which is essentially identical to the first embodiment but for the clock-wise screw of the handle;

FIG. 8 is a left side elevational view thereof;

FIG. 9 is a top plan view thereof;

FIG. 10 is a right, top, front perspective view of a third embodiment;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a left, top, front perspective view of a fourth embodiment which is essentially identical to the third embodiment but for the clock-wise screw of the handle;

FIG. 17 is a left side elevational view thereof; and,

FIG. 18 is a top plan view thereof.
